Primary Examiner — Rosemary K Tarcza*Assistant Examiner* — Sanjeev Paul(74) *Attorney, Agent, or Firm* — Brinks Gilson & Lione(57) **CLAIM**

I claim the ornamental design for an electric charger with AC-DC power converter, as shown and described.

DESCRIPTION

FIG. 1 is a front perspective view of a first embodiment of an electric charger with AC-DC power converter of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-section view with the internal parts omitted taken along the line 9-9 of FIG. 3;

FIG. 10 is a rear perspective view thereof shown in an alternate position in which an AC plug is rotated and exposed; FIG. 11 is a front perspective view of a second embodiment of an electric charger with AC-DC power converter of the present invention;

FIG. 12 is a rear perspective view thereof;

FIG. 13 is a front view thereof;

FIG. 14 is a rear view thereof;

FIG. 15 is a first side view thereof;

FIG. 16 is a second side view thereof;

FIG. 17 is a top view thereof;

FIG. 18 is a bottom view thereof;

FIG. 19 is a cross-section view with the internal parts omitted taken along the line 19-19 of FIG. 13; and,

FIG. 20 is a rear perspective view thereof shown in an alternate position in which an AC plug is rotated and exposed.
